James B. Roberts, Los Angeles, Calif.

Application June 15, 1946, Serial No. 130,743

Term of patent 14 years

(Cl. D34—13)

To all whom it may concern:

Be it known that I, James B. Roberts, a citizen of the United States, residing at 3627 Randolph Avenue, Los Angeles, in the county of Los Angeles and State of California, have invented a new, original, and ornamental Design for a Deck of Cards, of which the following is a specification, reference being had to the accompanying drawing, forming part thereof.

In the drawing:

- Figure 1 is an edge view of the cards.
- Figure 2 is a face view of the jack of spades.
- Figure 3 is a face view of the ace of spades.
- Figure 4 is a face view of the ace of clubs.
- Figure 5 is a face view of the queen of clubs.
- Figure 6 is a face view of the king of clubs.
- Figure 7 is a face view of the jack of hearts.
- Figure 8 is a face view of the queen of hearts.
- Figure 9 is a face view of the king of spades.
- Figure 10 is a face view of the queen of spades.
- Figure 11 is a face view of the joker.
- Figure 12 is a face view of the jack of clubs.
- Figure 13 is a face view of the king of hearts.
- Figure 14 is a face view of the ace of hearts.
- Figure 15 is a face view of the jack of diamonds.
- Figure 16 is a face view of the king of diamonds.

Cards from 2 to 10, inclusive, of all suits are conventional and the backs of all cards are also conventional.

I claim:

The ornamental design for a deck of cards, as shown and described.

JAMES B. ROBERTS.
